(57) **CLAIM**

We claim the ornamental design for a zinc-air hearing aid battery package, as shown and described.

DESCRIPTION

FIG. 1 is a perspective view of a zinc-air hearing aid battery package;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

FIGS. 2 through 7 are shown on an enlarged scale.

The broken lines shown in the drawing disclosure are for illustrative purposes only and form no part of the claimed design. The longer dashed lines are meant to represent perforation.
